UNITED STATES PATENT OFFICE.

JAMES MCRAE, OF LONDON, ENGLAND, ASSIGNOR OF ONE-HALF TO JOHN COOPER BROADBENT, OF HUDDERSFIELD, YORKSHIRE, ENGLAND.

APPARATUS FOR USE IN REFRIGERATING, HEATING, DRYING, IMPREGNATING, OR OTHERWISE TREATING GOODS.

SPECIFICATION forming part of Letters Patent No. 705,279, dated July 22, 1902.

Application filed March 5, 1901. Serial No. 49,862. (No model.)

To all whom it may concern:

Be it known that I, JAMES MCRAE, a subject of the King of England, residing and having my post-office address at 7 Fenchurch Avenue, London, E. C., England, have invented a certain new and useful Improved Apparatus for Use in Refrigerating, Heating, Drying, Impregnating, or Otherwise Treating Goods, of which the following is a specification.

This invention relates to an apparatus which may be used for refrigerating, heating, drying, impregnating, or otherwise treating goods in a closed atmosphere, and more especially for continuous work in the cooling of successive charges of goods—for example, chocolate confectionery and the like.

In the accompanying drawings, Figure 1 is the left half and Fig. 1^a the right half of a central vertical section of a refrigerating-chamber constructed according to this invention. Fig. 2 is the left half and Fig. 2^a the right half of a cross-section thereof on the line 1 1 of Fig. 1 and Fig. 1^a. Figs. 3 and 4 are detail views. Fig. 5 is a vertical radial section, and Fig. 6 a section on line VI VI of Fig. 5, respectively showing more particularly the construction of shutters for preventing the entrance of warm air to the chambers when the door is opened. Figs. 7 and 8 show a modified construction for operation of the shutters, and Fig. 9 is a detail view showing a fan for the circulation of air. Fig. 10 is a radial section, and Fig. 11 a front view, showing a further modified construction for operation of the shutters. Fig. 12 is a view of the door-latch. Fig. 13 is a horizontal section showing a roller for preventing passage of air past the lateral walls of the chamber opposite the door.

The apparatus comprises a chamber 1, preferably cylindrical, with its axis vertical, closed above and below by removable or other covers 2 and having its wall or walls and said covers made or filled with non-conductive material—for example, of sheet metal or wood with hollow spaces 3, filled with silicate cotton, slag-wool, or the like. In said chamber there is mounted to revolve a receiver 4 for the goods to be cooled, comprising a central shaft 5 and partitions 6, which, commencing radial to said

shaft, bifurcate and diverge, so as to continue parallel, respectively, each to the next partition in order to form a series of radial chambers, the walls 7 of which are for some length parallel to one another, as clearly shown in Fig. 2. On these parallel walls are suitable ledges 8, of wood, angle-iron, or other material, on which trays carrying the goods to be cooled may be placed. At one part of the wall of the main chamber is a door 9 for giving access to said radial chambers as each successively is brought by the revolution of the set of radial chambers in coincidence with said door. Above and below within this part of the main chamber are horizontal non-conductive partitions or shutters 10. One method of constructing these shutters is shown in Figs. 5 and 6. They are supported from the top and bottom covers 2 by brackets 11, and between the latter and the shutters are placed blocks of rubber or other resilient material 12 to serve as springs, so that when the radial chambers arrive between said shutters a tight closure will be effected and all communication shut off from the remainder of the interior of the main chamber. Countersunk screws 13 and thumb-nuts 14 are provided for purposes of adjustment to compensate for wear of the rubber blocks, and the shutters may be provided with beveled lateral edges, as shown, so that the top and bottom of the radial chambers may slide easily between the shutters.

A modified form of shutter is shown in Figs. 7 and 8. In this case the shutter 10 is hinged at 37 to the casing 1 of the main chamber and the central drum or well of the receiver has an annular rail 33 of undulating form, on which runs a pulley 34, mounted on a short shaft 35, having bearing in a block 36 on the shutter, so that on the receiver being revolved the said shutter is slightly raised and lowered for the purpose of avoiding the friction arising from the edges of the radial chambers engaging the spring-pressed shutters, as in the arrangement previously described. It should be remarked that the descending undulations of the rail 33 are made sufficiently deep to avoid any possibility of the shutter not closing tightly against the

radial chambers, and in this connection it is not necessary that the pulley 34 should be in contact with said lower parts of the rail in the course of its travel.

5 A further modification in the method of operating the shutters is shown in Figs. 10 and 11. In these figures the shutters 11 are supported by links 33, pivoted in pairs in brackets 34, attached to the covers or ends 2 of the casing and to the shutters. Circular rods 35 may connect the brackets, on which rods the links revolve, or short pivots may be used for this purpose, as shown. Fixed to the shutters at the end nearest the door are flat plates or 15 rods 36, acting as strikers, adapted to engage recesses or cut-away portions 37 in the top and bottom edges of the door 9, and pivoted to the front links are rods 38, passing to the outside of the casing through plates 39 and 20 provided with nuts 41 for adjustment. Helical springs 42 are placed around said rods 38 in suitable channels or apertures made therefor between the two walls of the casing 1, said springs bearing at one end against the 25 plates 39 and at the other against the exterior of the inside wall of the casing. The purpose of this mechanism is that on the door 9 being opened the springs, which are made sufficiently powerful, will pull forward 30 the links 33 through rod 38, and consequently bring the shutters tightly against the top and bottom edges of that chamber which happens to be opposite the door, thus cutting off all 35 communication with the rest of the cooling chamber. It will be seen that when the door is closed the shutters are quite clear of the chambers, thus considerably facilitating the rotary movement of said chambers. Guides 48, supported by brackets 53, are provided 40 for insuring the proper direction of movement of the shutters and prevent same from lateral play. The links 33 may be made adjustable as to their length, if desired. If desired, the shutters may project to engage into 45 each compartment or radial chamber, so that the door has to be closed to release same, as shown in Fig. 11.

In Fig. 12 is shown a latch for the door 9. This latch 49 is weighted and pivoted to the 50 casing at 50 and when the door is closed engages a catch 51 on the door, but when opened engages a rest 52 on the casing, as shown in dotted lines. The before-mentioned springs 42 may be made of such strength that on the 55 latch 49 being raised they will thrust the shutters with sufficient force to automatically open the door through the mechanism described and at the same time close the shutters.

60 In Fig. 13 is shown an arrangement to further shut off the compartment opposite the door from the rest of the chamber when the door is opened. This consists of a vertical roller 53 of approximately the same length as 65 the height of the compartment and mounted on a shaft 60. One of these rollers is placed on each side of the door in close proximity

thereto and bears against the wall of the receiver between the compartments. These rollers also avoid friction on revolution of 70 the receiver. A guard 55 is placed around the roller to protect same from the packing placed between the walls of the casing.

The interior of the main chamber may be cooled by any suitable means. In the drawings tanks 15 are arranged in sets of three and adapted to be filled with brine or other cooling medium, which is admitted at 16, and after circulating through all tanks, which are connected to each other by pipes 17, is ultimately discharged at 18. Condensation upon the exterior of the tanks 15 may be carried off by troughs 22 into the central drum of the receiver and thence by the annular trough 23 and pipe 24 into the trapped pipe 25, where the condensed liquid forms a seal for preventing the entrance of warm air. The receiver may be revolved by any convenient means—for instance, by an exterior hand-wheel 19 on shaft 40, at the other end of which 90 is a pinion 20, which gears either with a circular rack 21, fixed to the bottom of the receiver, as in Fig. 1, or, as in Fig. 10, with a beveled wheel 44 on the shaft 5.

An indicator 26 is mounted at the upper 95 end of central shaft 5 and serves to show when a chamber is opposite the door and which chamber has thus arrived, it being provided with figures or numbers corresponding to the said radial chambers. This indicator 100 consists of a circular band 27—for instance, of metal—supported from the central shaft by radial arms 28, which are fixed in a socket 29, keyed to the central shaft 5, as shown in Figs. 1 and 4.

30 and 31 represent an oil cup and pipe for the purpose of lubricating the lower end of shaft 5, which is mounted in a step-bearing 32.

A fan 38 may be placed in the lower part of the central drum of the receiver, as shown in Fig. 9, for the purpose of causing an upward circulation and distribution of the cold air, as it is found that the colder air tends to collect at the bottom of the main chamber and the warmer air above. This fan may be 115 mounted on a sleeve 39, loose on central shaft 5, and be operated by any suitable means—for instance, an electric motor. A suitable bell 56, Fig. 10, may surround the fan to assist in guiding the air upward through the 120 central well.

The apparatus can be used in the same way for heating instead of cooling or for drying, impregnating, or in any way treating goods in an atmosphere different from that prevailing outside the apparatus, and therefore requiring to be inclosed.

I declare that what I claim is—

1. The combination of a rotary holder comprising a plurality of radial compartments 130 each open above and below, with a casing closed above and below and having a doorway in the side wall thereof, said casing closely surrounding said holder at the sides thereof

but inclosing free spaces, above and below said holder, whereby free circulation of atmosphere is permitted within said casing vertically through said compartments, a door for closing said doorway and shutters above and below the rotary holder adjacent to the door of the casing, adapted to close above and below that compartment which is alined with the doorway when the door is opened for the purpose set forth.

2. The combination of a rotary holder comprising a plurality of radial compartments open above and below, with a casing closed above and below and having a doorway in the side wall thereof of a width and height equivalent to the width and height of each radial compartment, said casing closely surrounding said holder at the sides thereof but inclosing free spaces above and below said holder, a door for closing said doorway, shutters above and below the rotary holder adjacent to the door of the casing and means for operating said shutters to close above and below that compartment which is alined with the doorway when the door is opened for the purpose set forth.

3. The combination of a rotary holder comprising a plurality of radial compartments each open above and below with a casing closed above and below and having a doorway in the side wall thereof of a width and height equivalent to the width and height of each radial compartment, said casing closely surrounding said holder at the sides thereof but inclosing free spaces above and below said holder, whereby free circulation of atmosphere is permitted within said casing vertically through said compartments, a door for closing said doorway, shutters above and below the rotary holder adjacent to the door of the casing, adapted to close above and below that compartment which is alined with the doorway when the door is opened, and means for cooling the atmosphere in said casing.

4. The combination of a rotary holder comprising a plurality of radial compartments open above and below and surrounding a central shaft, with a casing closed above and below and having a doorway in the side wall thereof of a width and height equivalent to the width and height of each radial compartment, said casing closely surrounding said holder at the sides thereof but inclosing free spaces above and below said holder, a door for closing said doorway, shutters above and below the rotary holder adjacent to the door of the casing, adapted to close above and below that compartment which is alined with the doorway when the door is opened for the

purpose set forth, means for cooling the atmosphere in said casing in the space above the rotary holder and a fan for causing a circulation of said atmosphere in a direction upwardly centrally of said radial compartments into contact with said cooling means and downwardly through the compartments.

5. The combination of a rotary holder comprising a plurality of radial compartments open above and below and surrounding a central shaft with a casing closed above and below and having a doorway in the side wall thereof of a width and height equivalent to the width and height of each radial compartment, said casing closely surrounding said holder at the sides thereof but inclosing free spaces above and below said holder, a door for closing said doorway, shutters above and below the rotary holder adjacent to the door of the casing, means for operating said shutters to close above and below that compartment which is alined with the doorway when the door is opened for the purpose set forth, means for cooling the atmosphere in said casing comprising a series of refrigerating-pipes in the space above the rotary holder and a fan for causing a circulation of said atmosphere in a direction upwardly centrally of said radial compartments into contact with said cooling means and downwardly through the compartments.

6. The combination of a rotary holder comprising a plurality of radial compartments open above and below and surrounding a central shaft, with a casing closed above and below and having a doorway in the side wall thereof of a width and height equivalent to the width and height of each radial compartment, said casing closely surrounding said holder at the sides thereof but inclosing free spaces above and below said holder, a door for closing said doorway shutters above and below the rotary holder adjacent to the door of the casing, adapted to close above and below that compartment which is alined with the doorway when the door is opened for the purpose set forth, refrigerators for cooling the atmosphere in said casing in the space above the rotary holder, means for draining the condensation products on said refrigerator through the central shaft and an outflow-pipe for said condensation products adapted to be sealed thereby.

In witness whereof I have signed this specification in the presence of two witnesses.

JAMES MCRAE.
